UNITED STATES PATENT OFFICE.

THOMAS CORNELIUS SHEEHAN, OF UPPER MONTCLAIR, NEW JERSEY, ASSIGNOR TO WADE & BUTCHER CORPORATION, OF JERSEY CITY, NEW JERSEY, A CORPORATION OF NEW JERSEY.

POLISHING MACHINE.

Application filed September 22, 1923. Serial No. 664,269.

To all whom it may concern.:

Be it known that I, THOMAS C. SHEEHAN, a citizen of the United States, residing at Upper Montclair, county of Essex, and State of New Jersey, have invented a new and useful Improvement in Polishing Machines, of which the following is a specification.

This invention relates to a polishing method and apparatus.

Heretofore in the manufacture of certain articles, such for example as knife blades, it has been the practice to grind the forged blades in a lateral direction, then polish the same in substantially the same direction, then buff the same also in the same general lateral direction when a higher finish was desired than that afforded by the polishing operation. The initial grinding operation left lateral abradant marks on the ground surfaces of the blade; or in other words, left surfaces consisting of alternating grooves and ridges plainly visible to the naked eye. A fine abradant was of course used in the polishing operation, and this abradant not only acted on the tops of the ridges but on the bottom of the grooves, though under reduced pressure in the latter. Thus, as the tops of the ridges were worn away, the grooves were deepened to a lesser extent. As a result of the practice of polishing the blades in the same direction in which they were ground, the ridges were worn away and polished but the abradant marks were not entirely removed, so that abradant marks were visible even on the polished blade. And when the polished blades were buffed in the same direction in which they had been ground and polished, the sharp marks were removed but the surface of the blade still showed alternating flattened ridges and shallow grooves, though both were highly polished. It is very desirable that a knife blade be finished to present a polished surface free from even flattened ridges and shallow grooves; and it has been discovered that by polishing a laterally ground blade, or any article showing abradant marks, in a direction intersecting said marks, so that the abradant will act across the ridges, spanning the grooves, and without deepening the latter, as in the old method of polishing along the ridges and grooves, the ridges will be worn entirely away, that is, down to the bottom of the grooves, and the resultant surface

will be highly polished and free from the 55 ridges and grooves which heretofore have been unavoidable. The present invention therefore contemplates the use of a method of finishing an article bearing abradant marks which consists in polishing said article in a direction intersecting said marks, and involves the production of an apparatus for carrying this method into effect, in order, not only to produce a better finish on ground articles, but to do it automatically and at a 60 greatly reduced cost. The invention consists in certain methods, and in certain constructions and combinations which will be hereinafter fully described and then specifically pointed out in the claims hereunto appended. 65

In the accompanying drawings, which form a part of this specification and in which like characters of reference indicate the same or like parts, Fig. 1 is a side elevation of a machine constructed in accordance with the invention; Fig. 2 is a plan view of the structure shown in Fig. 1; Fig. 3 is a front end elevation of the structure shown in Figs. 1 and 2; Fig. 4 is a cross-sectional view taken on the line 4—4 in Fig. 1; Fig. 5 is a sectional plan view taken on the line 5—5 in Fig. 1; Fig. 6 is a detail view in elevation on an enlarged scale of the article holders, the active elements of the polishing device. and the means for supplying abradant thereto; Fig. 7 is a detail cross-sectional view taken on the line 7—7 in Fig. 6; Fig. 8 is a cross-sectional detail view taken on the line 8—8 in Fig. 6; Fig. 9 is a detail plan view on an enlarged scale of two of the active 70 elements of the polishing device, showing an article between the same, and means for pressing the active elements against the article; Fig. 10 is a detail view taken on the line 10—10 in Fig. 9; Fig. 11 is a sectional view of one of the adjustable cranks used for controlling and varying the amplitude of the polishing movement; Fig. 12 is a rear end elevation of the structure shown in Figs. 1, 2, 3 and 4; Fig. 13 is a detail view of the means for moving the article presenting means in and out of operative position; Fig. 14 is a side view, partly in section and on an enlarged scale, taken on the line 14—14 in Fig. 13; Fig. 15 is a plan view of a modification of the structures shown in Figs. 1 to 14 inclusive; and Fig. 16 is a view in elevation taken on the line 16—16 in Fig. 15. 75 80 85 90 95 100 105

In carrying the invention into effect, the article bearing abradant marks is polished in a direction intersecting said marks and when the article is a knife blade bearing 5 lateral abradant marks or abradant marks extending substantially in a lateral direction, the blade is polished in a direction substantially longitudinal with respect to the blade; and when an automatic apparatus is 10 used for the purpose of polishing articles by this method, there is provided a polishing device, means for presenting articles bearing abradant marks to said device, and mechanism for producing a relative movement 15 of said device and said presenting means in a direction intersecting said marks, in order to wear away the ridges produced in the initial grinding operation without deepening the grooves, and thus reduce the surface of 20 the article to a polished surface unbroken by ridges and grooves. In the best constructions, there is further provided means for varying the amplitude of said movement to accommodate articles of different lengths; means 25 for moving said presenting means in and out of operative position, to facilitate loading and unloading of the presenting means with articles; means for supplying abradant to said device to maintain the efficiency of its 30 active elements; means for moving the active element of said device in another direction to prevent uneven wear of said active element; and means for pressing the active element of 35 said device against the articles to cause the abradant carried by said element to act upon the articles under proper pressure. In the best constructions also, the article presenting means is provided with non-rigid clamping means to permit a slight relative movement 40 of the presenting means and article whereby the article automatically adopts its most efficient position with respect to the active element of the polishing device; the mechanism for producing a relative movement 45 of the device and presenting means includes means for moving the presenting means, for by this construction a large number of articles can be loaded in the machine and simultaneously polished more readily 50 than is otherwise possible; the polishing device includes a pair of polishing media acting on both sides of articles in the presenting means to simultaneously polish both sides of a series of articles and thus effect a 55 material saving in time and cost of operation; and said polishing device includes a plurality of pairs of polishing belts, and the presenting means includes a plurality of 60 article supports, one for each pair of belts, so that a plurality of series of articles may be simultaneously polished on both sides, thus still further saving time and reducing 65 cost of operation. The above mentioned devices, means, mechanism and parts may be widely varied in construction within the

scope of the claims, for the device selected to illustrate the invention is but one of many possible concrete embodiments of the same. The invention therefore is not to be restricted to the precise details of the structure shown and described. 70

Referring to the drawings, 17 indicates the bedplate of a machine constructed in accordance with the invention. This bedplate is supported by legs 18, 19 and 20 in a well known manner. The structure so far described serves to support the various elements of the machine to be hereinafter described. 75

As hereinbefore indicated, the machine is provided with a polishing device including polishing media acting on both sides of articles to simultaneously polish the same, and thus effect a saving of time and a reduction in cost of operation, although it is to be understood that the invention also contemplates the use of a single polishing medium where the nature of the article to be polished precludes the use of co-acting polishing media. The machine illustrated is provided with a plurality of co-acting polishing media in the form of polishing belts 21, 22, 23 and 24. The belt 21 overlies the belt 22 and the two belts, as a pair, overrun pulleys 25 and 26. Similarly, the belt 23 overlies the belt 24 and these two belts, as a pair, overrun pulleys 27 and 28. 90

In the machine illustrated, both pairs of belts are given slow linear movements for presenting to the articles to be polished an ever-changing polishing surface and for preventing undue wear of parts of said belts. The means used for producing this belt movement is as follows: the pulleys 25 and 27 are respectively mounted on vertical shafts 29-30 which are respectively journaled in bearings 31-32, Fig. 5, mounted on the bedplate 17 near one of its ends. The shafts 29-30 project through and below the bedplate 17 and upon their projecting ends 100 respectively carry intermeshing gears 33-34 whereby they are caused to rotate in unison and drive the two pairs of belts in unison. The shaft 29 above the gear 33 carries a worm wheel 35 by means of which it is driven. This worm wheel is driven by a worm 36 which is mounted on a shaft 37 journaled in a bracket 38 bolted to the under side of the bedplate 17 before referred to. One end of the shaft 37 carries a sprocket 39 over which runs a sprocket chain 40, and this sprocket chain also overruns a sprocket 41 fast on a shaft 42 which is journaled in a bearing 43 bolted to the leg 18 and in a bearing 44 bolted to the leg 20. The shaft 42 is the main power shaft of the machine and it is driven by means of a belt 45 overrunning fast and loose pulleys 46-47 mounted on the end of the shaft adjacent the bearing 44 and outside the leg 20. A 110

115

120

125

130

suitable belt shifting device, not shown, is used for shifting the belt from the loose to the fast pulley or vice versa, when it is desired to start or stop the machine. While the mechanism just described is sufficient for moving the belts when the resistance of the belt to movement is not too great, the machine illustrated is also provided with means for driving the pulleys 26-28 in order that both ends of both belt loops may be driven. With this end in view, the pulley 26 is fast on a vertical shaft 48, and similarly the pulley 28 is fast on the vertical shaft 49, these shafts being respectively journaled in adjustable bearings 50-51, Fig. 5, mounted to slide in blocks 52-53 suitably bolted to the bedplate 17. The bearings 50-51 are adjustably moved in the blocks 52-53 by means of hand screws 54-55 operating in a well known manner to independently tighten the pairs of belts 21-22 and 23-24. The shafts 48-49 project through and are journaled in angle bearings 56-57 below the bedplate 17. The shaft 48 carries a bevel pinion 58 which is in mesh with a bevel pinion 59 splined on a shaft 60, the latter being journaled in a bearing 61 bolted to the leg 18 and in a bearing 62 bolted to the leg 20. Adjacent the bearing 62, the shaft 60 carries a bevel pinion 63 in mesh with and driven by a bevel pinion 64 on the extreme lower end of the shaft 29 before referred to. Similarly, the shaft 49 carries a bevel pinion 65 which is in mesh with a bevel pinion 66 splined on a shaft 67, the latter being driven from the shaft 30 as the shaft 60 is driven from the shaft 29; that is to say, by a pair of bevel pinions the same in construction and operation as the pinions 63 and 64. When a large number of articles is to be polished simultaneously, their resistance to the linear movement of the belts 21, 22, 23 and 24 is great and the four-pulley drive just described is sufficient to overcome this resistance and prevent slippage of the belts on the pulleys.

In the machine illustrated, means are provided for presenting articles bearing abradant marks to the polishing device above described, and this means includes a plurality of article supports, so that a plurality of series of articles may be simultaneously polished on both sides, to still further save time and reduce cost of operation. In the machine illustrated, both runs of both pairs of belts are used for polishing purposes and for this reason four article supports are provided, each supporting a series of fifteen articles to be polished. These supports are generally indicated by the reference character 68, see Fig. 4. One of the supports 68 is bolted to a bar 69, two of them are bolted to a bar 70, and the 4th one is bolted to a bar 71. The bars 69, 70 and 71 are bolted to crossheads 72-73, one at each end of the machine. The supports 68 are all alike and a description of one will therefore answer for all four. Each support 68 is provided with a series of clamping devices, each including a block 74 somewhat loosely held on the support 68 by means of two studs 75 which are riveted into the support 68 and provided with heads overlying the blocks, a slight clearance being left between the block and stud heads. Each block is further provided with an aperture 76 through which the tang 77 of a knife blade may be passed when the articles to be polished are knife blades. The tangs 77 are clamped in the blocks 74 by means of wing nuts 78 of well known construction and operation. The supports 68 are located in the machine to hold the knife blades, when knife blades are to be polished, between the belts 21-22 and the belts 23-24, one support 68 being located over each run of both pairs of belts. The purpose of mounting the blocks 74 somewhat loosely on the supports 68 is to permit a slight movement of the knife blade, whereby it adjusts itself between the polishing belts to facilitate even pressure of the belts on the opposite surfaces of the blades. It is to be understood that when articles other than knife blades are to be polished, different forms of clamping devices will be substituted for those shown in the drawings.

The machine illustrated is provided with mechanism for producing a relative movement of the polishing device and the article presenting means in a direction intersecting the abradant marks on the articles to be polished in order to cause the polishing device to wear away the ridges produced in the initial grinding operation, without deepening the grooves, thus reducing the surface of the article to a polished surface unbroken by ridges and grooves, and this mechanism includes means for moving the presenting means, the polishing device being operative in fixed position although the active elements of the latter, that is, the belts 21, 22, 23 and 24, have a linear movement of their own which is independent of the relative movement whereby the polishing function is effected. With the above end in view, the crossheads 72-73 are respectively mounted to reciprocate vertically on posts 78-79, one of which is secured to each end of the bedplate 17 before referred to. Each of the crossheads 72-73 is provided with a stud 80 held in position by means of a set screw 81. Pivotally connected with each of the studs 80 is a connecting rod 82 which is also pivotally connected with a crankpin 83, carried by a crank 84, the cranks 84 being fast on the ends of a shaft 85 which is journaled in suitable bearings in the legs 18, 19 and 20 before referred to. On one side of the leg 19 the shaft carries a balance wheel 86, and on the other side of the same leg the shaft

carries a gear 87. This gear 87 is in mesh with and is driven by a pinion 88 fast on the shaft 42 which, it will be remembered, is the main power shaft of the machine. By means of the mechanism just described, the crossheads 72-73, carrying the four supports 68 loaded with sixty knife blades or other articles to be polished, are given a rapid vertical reciprocating movement which causes the knife blades to slide down and up between the belts of each pair of belts, and consequently between the active elements of the polishing device; and since the knife blades are always initially ground in a lateral direction, the polishing movement is in a direction intersecting the abradant marks left on the blades during the grinding operation; or, in other words, in a longitudinal direction with respect to the knife blades. It will be understood that while the article presenting means is rapidly reciprocating in a vertical direction, the belts 21, 22, 23 and 24 of the polishing device are moving in a linear direction very slowly, the purpose of the belt movement being to prevent the reciprocating blades or other articles from wearing grooves across the same, and to present to the reciprocating blades an everchanging polishing surface.

Means are provided for pressing the active elements of the polishing device against the blades or other articles to be polished. With this end in view, there is provided a series of bars 89 extending along the machine, one on either side of each run of each pair of belts and in the lateral wake of said belts. These bars are supported from the bedplate 17 by means of brackets 90 bolted to said bedplate, and each bar carries, in the wake of each knife blade—when knife blades are to be polished, four pressure devices, each consisting of a clamp 91 held by means of a set screw 92 on the bar 89, and provided with a stud 93 around which is coiled a pressure spring 94. One end of each spring 94 bears against the clamp 91, while the other end bears against a plate 95 bearing against the belts 21, 22, or 23, 24, as the case may be. The plates 95 are of sheet metal and the upper section of each is provided with a series of stamped out spring tongues 96, one below each clamping block 74 before referred to, and one of the springs 94 bears against each of these spring tongues. A modified form of pressure device is shown in Fig. 9. It consists of a pair of shoes 97-97, each carrying a pair of studs 98-98 and a screw 99, the studs and screw being freely movable in suitable apertures in the bar 89 before referred to. Between the shoe 97 and the bar 89, pressure springs 100 are coiled around the studs 98. It will be readily understood that the pressure exerted against the polishing belts, and through the latter on the surface of the article to be

polished, is dependent upon the thrust of the springs 94, which of course can be changed by substituting similar springs of different thrust. Heavy pressure, however, is not desired, for it has been found that better results are obtained when the pressure is light and the relative movement of the article presenting means and of the polishing device is continued for a considerable time.

For the purpose of maintaining a high efficiency of the active elements of the polishing device, means are provided for supplying abradant to said device. In the machine illustrated, and with this end in view, there are provided troughs 101 supported by the brackets 90 before referred to, and containing abradant in the form of the finest flower of emery in thick oil. By an inspection of Figs. 4 and 6, it will be seen that the knife blades 102 dip into this abradant at the lower end of the reciprocating movement of the presenting means, and it will be readily understood that upon the upward movement of the presenting means each blade will carry a little of the abradant to the surface of the belts 21-22 or 23-24, as the case may be, and spread it thereon, this spreading action being aided by the slow linear movement of the belts. Any excess of abradant carried up falls back into the trough from which it came. The active elements of the polishing device are thus kept in highly efficient condition.

When articles are to be loaded into the presenting means, it is desirable that the latter be moved out of operative position with respect to the polishing device, and means are provided for this purpose. In the machine illustrated, the means for moving the presenting means in and out of operative position includes a shaft 103 journaled in bearings 104 at the top of the posts 78-79 before referred to. This shaft carries at one end an operating handle 105 by means of which it is rocked when desired. Loosely mounted upon the shaft 103, between the bearings 104-104, is a rotatable sleeve 106, and this sleeve carries at each of its ends a disk 107, which in turn carries a pin 108. The disks 107 are fast on and rotatable with the sleeve 106. Each of the pins 108 is adapted to engage a bent arm 109 fulcrumed at 110 to a disk 111 fast on the shaft 103. Each arm 109 is provided with a recess 112 which is adapted for engagement with a stud 113 carried by each of the crossheads 72-73 before referred to. The upper end of each connecting rod 82, before referred to, terminates in a block 114 provided with a slot 115 through which a clamping bolt 116 extends, this bolt in each case being threaded into the main part of the connecting rod 82. When it is desired to throw the presenting means out of operative position with respect

to the polishing device for unloading and reloading purposes, the bolts 116 are loosened, the lever 105 is thrown upward to cause the fulcrum of the arm 109 to move downward below the shaft 103. The sleeve 106 is then rotated to cause the recesses 112—112 of the arms 109—109 to engage the studs 113—113. The lever 105 is then moved downwardly to its normal position, as shown in Fig. 13. 10 This brings the fulcrum 110 above and to the right of the shaft 103, or in other words, past dead center of a line intersecting the stud 113 and the shaft 103. And there it remains until unloading and reloading has 15 taken place, and the presenting means has again been lowered into operative position, and the bolts 116 again tightened.

Since the machine is designed to polish articles of different lengths, and since the 20 polishing device is operative in a fixed position, it is desirable to vary the amplitude of the relative movement of the presenting means and the polishing device to avoid lost motion when short articles are to be polished. 25 Means are therefore provided for varying the amplitude of the said movement, and this means consists of devices whereby the stroke of the cranks 84 may be varied. As shown, the crankpin 83 is provided with an 30 integral rectangular head 117, see Fig. 11; and this head is movable in a slideway 118 formed in the crank 84. The head 117, and consequently the crankpin 83, is moved toward or away from the axis of the shaft 85 35 by means of a screw 119 of well known construction and operation. It will be readily understood that the variation of crank throw which can be effected by means of the device just described will result in varying the amplitude of the relative movement of the presenting means and polishing device.

The machine illustrated and described is 40 designed to simultaneously polish both surfaces of sixty knife blades, when knife blades are to be polished. It has been found that the best results are obtained by using the finest obtainable abradant and continuing the polishing operation for a considerable time, an hour or more. A single operator, 45 however, can handle four such machines for there is nothing for him to do except load and unload them, so that one operator can keep three machines running all the time, and four machines running a part of the time. He can therefore polish upwards of 50 two hundred blades per hour as against ten polished by hand methods heretofore used, thus greatly reducing the cost of operation 55 and also producing better products with machinelike precision.

In view of the foregoing, a detailed description of the operation of the device is 60 deemed unnecessary and is therefore omitted in the interest of brevity.

65 In the modified form of article presenting

means and polishing device shown in Figs. 15 and 16, there are ten pairs of belts 120 and ten supports 121, each support being provided with clamping devices 123 similar in all respects to those used in the machine illustrated in Figs. 1 to 14 inclusive. The belts 120 are not endless, but at their opposite ends are secured to crossheads 124 sliding on bars 125 supported by blocks 126 mounted on the bedplate 17. Each crosshead is connected to 70 one end of a lever 127 fulcrumed at 128 to a block 129 secured to the under side of the bedplate 17, the opposite end of each of the levers 127 being connected to a parallel bar 129'. This bar carries a stud 130 engaging a fork 131 on an oscillating lever 132 fulcrumed at 133 to a suitable part of the machine and oscillated by suitable means, not shown, the purpose of this oscillation being to produce a reciprocating movement of the 75 belts 120 for the same purpose that the belts 21, 22, 23 and 24 in the preferred machine, are given their linear movement.

80 It will be understood that in the machine illustrated in Figs. 1 to 14 inclusive, and also in the machine in part illustrated in Figs. 15 and 16, the polishing device includes a plurality of pairs of polishing belts mounted in parallelism, and the presenting means is correspondingly provided with means for 85 supporting a plurality of series of articles in parallelism.

89 What is claimed is:

1. A polishing machine comprising a flat 100 polishing medium, means for presenting articles to said medium, means for reciprocating said presenting means in parallelism with said medium, and means for moving said medium in a direction transverse to the movements of said presenting means. 105

2. A polishing machine comprising a flat 110 polishing medium, means for presenting articles to said medium, means for reciprocating said presenting means in parallelism with said medium, means for moving said medium in a direction transverse to the movements of said presenting means, and means for varying the amplitude of the movements of said presenting means.

3. A polishing machine comprising a flat 115 polishing medium, means for presenting articles to said medium, means for reciprocating said presenting means in parallelism with said medium, means for moving said medium in a direction transverse to the movements of said presenting means, and means for moving said presenting means in and out of operative position.

4. A polishing machine comprising a flat 120 polishing medium, means for presenting articles to said medium, means for reciprocating said presenting means in parallelism with said medium, means for moving said medium in a direction transverse to the movements of said presenting means, and 125

130

means for supplying abradant to said medium.

5. A polishing machine comprising a flat polishing medium, means for presenting articles to said medium, means for reciprocating said presenting means in parallelism with said medium, means for moving said medium in a direction transverse to the movements of said presenting means, and 10 means for pressing said medium against the articles.

6. A polishing machine comprising a flat polishing medium, means for presenting articles to said medium, means for reciprocating said presenting means in parallelism with said medium, means for moving said medium in a direction transverse to the movements of said presenting means, means for varying the amplitude of the movements 15 of said presenting means, means for moving said presenting means in and out of operative position, means for supplying abradant to said medium, and means for pressing said medium against the articles.

7. A polishing machine comprising a flat polishing medium, means for presenting articles to said medium, means for reciprocating said presenting means in parallelism with said medium, and means for moving 30 said medium in a direction transverse to the movements of said presenting means, said medium being active on opposite sides of the articles.

8. A polishing machine comprising a flat polishing medium, means for presenting articles to said medium, means for reciprocating said presenting means in parallelism with said medium, and means for moving 40 said medium in a direction transverse to the movements of said presenting means, said medium including endless belts acting on opposite sides of the articles.

9. A polishing machine comprising a flat polishing medium, means for presenting articles to said medium, means for reciprocating said presenting means in parallelism with said medium, and means for moving 45 said medium in a direction transverse to the movements of said presenting means, said medium including an endless belt within another said belt acting on opposite sides of the articles.

10. A polishing machine comprising a flat polishing medium, means for presenting articles to said medium, means for reciprocating said presenting means in parallelism with said medium, and means for moving 55 said medium in a direction transverse to the movements of said presenting means, said moving means acting to move said medium horizontally.

11. A polishing machine comprising a flat polishing medium, means for presenting articles to said medium, means for reciprocating 60 said presenting means in parallelism

with said medium, and means for moving said medium in a direction transverse to the movements of said presenting means, said moving means acting to move said medium continuously.

12. A polishing machine comprising a flat polishing medium, means for presenting articles to said medium, means for reciprocating said presenting means in parallelism with said medium, and means for moving 75 said medium in a direction transverse to the movements of said presenting means, said moving means acting to move said medium in one direction only.

13. A polishing machine comprising a flat polishing medium, means for presenting articles to said medium, means for reciprocating said presenting means in parallelism with said medium, and means for moving 80 said medium in a direction transverse to the movements of said presenting means, said moving means acting to move said medium at a speed lower than that of said reciprocating means.

14. A polishing machine comprising a flat polishing medium, means for presenting articles to said medium, means for reciprocating said presenting means in parallelism with said medium, and means for moving 85 said medium in a direction transverse to the movements of said presenting means, said moving means acting to move said medium horizontally and continuously and at a speed lower than that of said reciprocating means.

15. A polishing machine comprising a flat polishing medium, means for presenting articles to said medium, means for reciprocating said presenting means in parallelism with said medium, and means for moving 90 said medium in a direction transverse to the movements of said presenting means, said moving means being worm driven.

16. A polishing machine comprising a flat polishing medium, means for presenting articles to said medium, means for reciprocating said presenting means in parallelism with said medium, and means for moving 100 said medium in a direction transverse to the movements of said presenting means, said presenting means including means for holding the articles during the polishing operation.

17. A polishing machine comprising a flat polishing medium, means for presenting articles to said medium, means for reciprocating said presenting means in parallelism with said medium, and means for moving 110 said medium in a direction transverse to the movements of said presenting means, said presenting means including independent clamping devices for independently holding the articles during the polishing operation.

18. A polishing machine comprising a flat polishing medium, means for presenting articles to said medium, means for reciprocating 120

ing said presenting means in parallelism with said medium, and means for moving said medium in a direction transverse to the movements of said presenting means, said 5 presenting means including a frame provided with rows of clamping devices for independently holding the articles during the polishing operation.

19. A polishing machine comprising a flat 10 polishing medium, means for presenting articles to said medium, means for reciprocating said presenting means in parallelism with said medium, and means for moving said medium in a direction transverse to the 15 movements of said presenting means, said presenting means acting to present the articles to said medium in a plurality of rows.

20. A polishing machine comprising a flat 20 polishing medium, means for presenting articles to said medium, means for reciprocating said presenting means in parallelism with said medium, and means for moving said medium in a direction transverse to the 25 movements of said presenting means, said presenting means being vertically movable.

21. A polishing machine comprising a flat 30 polishing medium, means for presenting articles to said medium, means for reciprocating said presenting means in parallelism with said medium, and means for moving said medium in a direction transverse to the movements of said presenting means, said presenting means being vertically movable 35 and provided with rows of clamping devices for independently holding and presenting the articles to said medium in a plurality of rows.

22. A polishing machine comprising a flat 40 polishing medium, means for presenting articles to said medium, means for reciprocating said presenting means in parallelism with said medium, and means for moving said medium in a direction transverse to the 45 movements of said presenting means, said reciprocating means being crank-actuated.

23. A polishing machine comprising a flat 50 polishing medium, means for presenting articles to said medium, means for reciprocating said presenting means in parallelism with said medium, and means for moving said medium in a direction transverse to the

movements of said presenting means, said reciprocating means including crank-actuated rods connected with said presenting 55 means.

24. A polishing machine comprising a flat 60 polishing medium, means for presenting articles to said medium, means for reciprocating said presenting means in parallelism with said medium, and means for moving said medium in a direction transverse to the movements of said presenting means, said reciprocating means including adjustable 65 cranks for varying the amplitude of the reciprocations, and rods connecting said cranks with said presenting means.

25. A polishing machine comprising a flat 70 polishing medium, means for presenting articles to said medium, means for reciprocating said presenting means in parallelism with said medium, and means for moving said medium in a direction transverse to the movements of said presenting means, and means for supplying abradant to said medium including a trough into which the articles dip and from which they convey abradant to said medium. 75

26. A polishing machine comprising a flat 80 polishing medium, means for presenting articles to said medium, means for reciprocating said presenting means in parallelism with said medium, means for moving said medium in a direction transverse to the movements of said presenting means, and 85 means for moving said presenting means in and out of operative position including a manually actuated rock-shaft and operative connections.

27. A polishing machine comprising a flat 90 polishing medium, means for presenting articles to said medium, means for reciprocating said presenting means in parallelism with said medium, means for moving said medium in a direction transverse to the movements of said presenting means, and means for moving said presenting means in and 95 out of operative position including a manually actuated rock-shaft and a plurality of connecting hooks for engagement with said presenting means. 100

In testimony whereof, I have signed my name to this specification.

THOMAS CORNELIUS SHEEHAN.
